Primary Examiner — Christian P. McLean*Assistant Examiner* — Nader Abadir(57) **CLAIM**

The ornamental design for a slidable strainer, as shown and described.

DESCRIPTION

FIG. 1 is a top-front-left perspective view of a slidable strainer showing my design;

FIG. 2 is a bottom-front-right perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a top plan view thereof;

FIG. 8 is a bottom plan view thereof;

FIG. 9 is a reduced top-front-right perspective view thereof, wherein the slidable strainer is retracted within a can;

FIG. 10 is a reduced bottom-front-left perspective view thereof, wherein the slidable strainer is retracted within the can;

FIG. 11 is a reduced top-front-right perspective view thereof, wherein the slidable strainer is extended out of the can; and,

FIG. 12 is a reduced bottom-front-left perspective view thereof, wherein the slidable strainer is extended out of the can.

The broken line showing of a can in FIGS. 9 through 12 is for the purpose of illustrating environmental structure and forms no part of the claimed design.
